UNITED STATES PATENT OFFICE.

JAMES G. NORTON, OF ELTINGVILLE, NEW YORK, ASSIGNOR TO UNITED SHOE MACHINERY CORPORATION, OF PATERSON, NEW JERSEY, A CORPORATION OF NEW JERSEY.

SPLITTING MACHINE.

Application filed October 9, 1920, Serial No. 415,810. Renewed January 5, 1924.

To all whom it may concern:

Be it known that I, JAMES G. NORTON, a citizen of the United States, residing at Eltingville, S. I., in the county of Richmond and State of New York, have invented certain Improvements in Splitting Machines, of which the following description, in connection with the accompanying drawings, is a specification, like reference characters on the drawings indicating like parts in the several figures.

This invention relates to machines for operating upon pieces of stock and is herein described as embodied in a machine for operating upon heel-lift blanks to reduce each blank which is not of a uniform thickness throughout to a uniform thickness.

Leather heel lift blanks as they come from the dieing-out machine are of different thicknesses, and many of the blanks considered individually are not uniform in thickness throughout. It is desirable that each uneven blank be reduced to a uniform thickness such that the thickness of the finished lift 25 is the greatest which could be produced from the given blank.

According to one feature of the invention the amount of variation of a blank with respect to a selected characteristic is determined, and means controlled by the variation-determining means is provided for changing that characteristic. In the illustrative machine the amount of difference in thickness between the thickest and the thinnest locality of each uneven blank is determined, and then a skiving mechanism is set in accordance with this thickness-difference to reduce the blank to a uniform thickness.

Many of the heel-lift blanks, as they come from the dieing out machine, are of uniform thickness throughout or are so nearly of uniform thickness that they may be considered to be of uniform thickness. Such blanks are suitable for use in heels without further treatment, and should not be skived or otherwise reduced in thickness. According then to another feature of the invention the means for changing the selected characteristic of the blank is rendered inoperative when a given blank does not vary in that characteristic or varies so little that the variation is immaterial so far as the use to which the blank is to be put is concerned. In the illustrative machine if a blank is

found not to vary in thickness or not to 55 vary beyond a predetermined standard, the skiving mechanism is rendered inoperative and the blank passes through the machine without being operated upon.

These and other features of the invention, 60 including certain details of construction and combinations of parts will be described as embodied in an illustrative machine and pointed out in the appended claims.

Referring now to the accompanying drawings,

Fig. 1 is a side elevation of a machine in which the present invention is embodied;

Fig. 2 is a perspective of the working parts of the machine;

Fig. 3 is a perspective showing more particularly the operation of the testing mechanism upon the setting mechanism;

Fig. 4 is a perspective showing a blank in process of being skived.

Fig. 5 is a detail principally in elevation of a portion of the setting mechanism;

Fig. 6 is a perspective of the rolls of the lower feed member and their driving mechanism,

Fig. 7 is a perspective of the main shaft of the machine showing more particularly the controlling cams and their associated levers, and

Fig. 8 is a perspective of the mechanism 85 for locking the lower blank engaging member from vertical movement, the mechanism being shown in its locking position.

Referring first more particularly to Fig. 1, a brief outline of the operation of the machine will be given. The blanks, herein shown as heel lift blanks 100, are stacked in a magazine 11 and fed successively by a feed slide 13 first to a testing or detecting mechanism located beneath a rigid plate 15 and 90 then to a skiving mechanism located at the rear of the machine. The testing mechanism, in the illustrative machine, finds the difference in thickness between the thickest and the thinnest locality of a plurality of 100 selected localities in the blank and controls the setting of the upper member 17 of the skiving mechanism so that this member is set in accordance with this thickness-difference. The testing mechanism is now released from engagement with the blank, and the blank is fed by a second movement of the feed slide 13 to the skiving mechanism.

Just before the forward end of the blank reaches the skiving knife, that member of the skiving mechanism which engages the under side of the blank, hereinafter referred to as the lower member 19, is caused to rise so that the blank is then engaged on both its upper and lower sides. The feed slide is then returned to its initial position, and the blank is advanced by power-driven rolls, 10 carried by the lower member 19, to the skiving knife 21.

Referring now to Fig. 4 in connection with Fig. 1, wherein a blank 100 is shown in process of being skived, the general operation of the skiving mechanism will be described. The knife 21 is stationary, and the amount of stock to be removed from the blank is determined primarily by the position of the upper member 17 with respect 20 to the knife. This member comprises a thick plate having yieldingly mounted in it a series of small blocks 23 which are urged downward at all times by springs 25, the blocks being held from being pushed 25 out of the recesses in which they are mounted by a thin plate 27 which is fastened to the under side of the thick plate. The thin plate has openings the edges of which overlie slightly the edges of the recesses in which 30 the blocks 23 are mounted and are adapted to engage shoulders on the blocks and thereby limit the extent of downward movement of the blocks. Each block has mounted in it an idle roll 29 the lowermost elements 35 of the rolls forming the effective pressing face of the upper blank-engaging member. This member is normally in raised position well above the plane of the cut of the knife, and is moved down into the proper position 40 by the testing mechanism and certain connections in response to the thickness-difference of the lift as determined by the testing mechanism. When the blocks 23 are pushed up into their fully retracted positions their upper faces contact with the flat 45 upper walls of the sockets in the thick plate, and the lowermost elements of the rolls 29 then lie substantially in the plane of the lower face of the thin plate 27 and present 50 an unyielding pressing surface.

The lower member 19 has mounted in it five power driven feed rolls 31, the axes of which are stationary with respect to the plate. This member is normally well below 55 the plane of the cut of the knife and is brought up against the blank after the upper member 17 has been set and the blank has been fed by the feed slide 13 into a position in which its leading edge is close 60 to the knife. The blank-engaging surface of the lower member is thus formed by the upper portions of the rolls 31 and is rigid during the skiving operation as will presently be described.

Considering more in detail the setting and

operation of the skiving mechanism with relation to the amount of thickness-difference found by the testing or detecting mechanism to be present in a given blank, the upper member 17 is moved down and held 70 rigidly against upward movement in a position such that the distance from the plane of the cut of the knife to the plane of the rigid blank-engaging surface of the member equals the amount of this thickness-difference. By the expression "plane of the rigid blank-engaging surface of the member" is meant substantially the plane of the under surface of the thin plate 27 since, when the small blocks 23 are moved to their 80 upper limits, the lower elements of the rolls 29 are substantially in this plane. After the upper member has been thus set, the blank is fed forward, as has been described, until its forward end is close to the knife. The lower member 19 is then raised yieldingly through a heavy spring until it forces the blank firmly against the upper member, whereupon it also is held rigidly from movement either toward or away from the 85 blank. The blank now lies flat upon the upper elements of the rolls 31, being held flat against these rolls by the presser rolls 29 the supporting springs of which are of sufficient strength to accomplish this. The lower surface of the blank is thus maintained in a horizontal plane which is parallel to the plane of the cut of the knife so that the finished article, which eventually passes beneath the knife, will be of uniform thickness throughout. The upper surface of the blank, assuming the blank to be of uneven thickness, does not lie in a horizontal plane but in an inclined plane if the blank is 90 regularly tapered from end to end or at various levels if there are thick spots separated by thin spots. Assuming for convenience of explanation that the blank is thickest at its leading edge and tapers regularly to its rear or following edge, the block 23 nearest the knife will be pushed up to the limit in its socket so as to be no longer yielding, and the remaining blocks 23 will extend from their sockets each more than 95 the preceding one. Consequently the chip removed by the knife will be thicker at the 100 forward than at the rearward end, the finished articles being of a uniform thickness throughout approximately equal to the distance between the plane of the cut of the knife and the plane of the upper elements of the rolls 31. With such a mechanism a series of blanks each of which has a thickness difference (that is a thickness different 105 in one locality from that in another) and which also differ one from another in their general or average thickness dimensions may be skived automatically so as to produce from such blanks finished articles each 110 of the maximum uniform thickness possible 115

from the blank from which it was produced. The upper member 17 is primarily a gaging member which is set in accordance with the thickness-difference of a blank regardless of the actual general or average thickness of the blank; and the lower member 19 is primarily a gripping and feeding member. It should be noted that after the upper member has been set and the lower member 10 pushed up against the blank to grip and feed it to the knife, the distance from the plane of the upper elements of the rolls 31 to the lower element of that roll 29 which is pushed up to the limit of its upward movement and is therefore pressing rigidly against the blank is equal to the thickness of the thickest locality of the blank.

Referring once more to Fig. 1 with occasional reference to Fig. 7, the feed slide 13 is slidably mounted upon the table 33 of the machine and is urged at all times backward (to the left in Fig. 1) by a spring 35 which is fastened at one end to a pin 37 carried by the feed slide and at the other 25 to a pin 39 carried by the frame of the machine. Fast to the pin 37 is one end of a strap 41, the other end of which passes around a roll 43 and is fastened to a pin 45 carried by the frame. The roll 43 is carried 30 at the upper end of an arm 47 fulcrumed at 49 upon a stationary pivot, said arm having a tail which is adapted to engage alternately adjustable stops 51, 53 which are threaded 35 through bosses on the side of the frame of the machine. An extensible link 55, the parts of which are at all times urged toward each other by a spring 57, is pivoted at one end to the arm 47 and at the other to an arm 59, said arm being pivoted to the frame 40 at 61 and carrying at its upper end a roll 63 which co-operates with a cam 65 fast to a rotary shaft 67. This shaft has fast upon it a large gear 69 with which meshes a small gear 71 on a short shaft 73 having fast upon 45 its outer end a pulley 75 which is driven continuously by a belt 77 from any suitable source of power. The cam 65 rotates in the direction indicated by the arrow and is shaped to cause the feed slide 13 to move quickly to a position beneath the plate 15 and above the testing or detecting mechanism, then to remain stationary during the testing operation, then to move quickly forward to present the tested blank to the splitting mechanism and finally to be returned to the initial position shown. It should be noted that by reason of the strap connection 41, the movement of the feed slide is twice as great as the bodily movement of the roll 43. The walls of the magazine which holds the blanks are adjustable horizontally to provide for blanks of different sizes and vertically to provide for blanks of different thicknesses as best appears in 60 Fig. 2, but the construction of the magazine 65

will not be described in detail since it forms no part of the present invention. Inasmuch as heel-lift blanks are commonly somewhat warped, a weight 79 is placed upon the top of the stack. 70

As has been explained above, the blank to be operated upon is first brought into position beneath the plate 15 above the testing mechanism and caused to pause in this position during the testing operation and the setting of the upper blank-engaging member 17 of the splitting mechanism. Referring now more particularly to Figs. 2 and 3, the testing mechanism and its mode of operation will be described. The under face of the plate 15 serves as an abutment against which the blank is pressed by detectors or testers in the form of idle rolls 81, five being employed in the illustrative machine. Each roll is mounted in a yoke 83 which is square in cross-section and passes through a square hole in a plate 85. Each yoke has a stem 87 which passes through a hole in a second plate 89, there being a spring 91 encircling each stem and acting to push the yoke upwardly and a collar 93 on each stem below the plate 89 to limit the extent of upward movement of the yoke. The plates 85, 89 are part of a frame which comprises the plates and a connecting U-shaped member 95 the upright arms of which are vertically slid able in guideways in the frame of the machine. 85 90 95

When a blank has been fed into position above this testing or detecting mechanism, the frame, comprising the plates 85, 89 and the U-shaped supporting member 95 is raised to cause the detecting rolls 81 to press the blank firmly against the under face of the plate 15. In order to produce this raising movement the base of the U-shaped member 95 has depending lugs carrying a pin 97 which is received in the forked end of a lever 99 fulcrumed near its middle about a rod 101 and carrying at its remote end a roll 102 arranged to run on a properly shaped cam 104 on the shaft 67. When the frame carrying the detecting rolls 81 is thus raised, the rolls, because of their yielding supports, will stand at different levels according to the thickness of the blank at the localities engaged by the rolls. Of course a given blank may be of uniform thickness throughout, but that case will be discussed later. For the present it will be assumed, in order to promote clearness of explanation, that the blank varies in thickness at different localities and is thickest at one locality and thinnest at another. In such case one detector 81 will be higher than any of the others and one will be lower. In Fig. 3 these two particular detectors 81 are shown, the right-hand one engaging the thinnest locality in the blank 100 and the left-hand one engaging the thickest locality, the difference 110 115 120 125 130

in height between these two detectors being the thickness-difference in accordance with the amount of which the upper member 17 of the skiving mechanism is to be set. In the illustrative machine an intermediate controlling member 103 is first set and then the upper member 17 of the skiving mechanism is set from this member. The controlling member 103 is T-shaped, the head and stem, except the left-hand end of the head, being substantially square in cross-section. The stem has a socket to receive a supporting spindle 105 which fits loosely in the socket; and the right-hand end of the head of the T is vertically slidable in a vertical rectangular guideway formed in the frame 107 of the machine. The left-hand end of the head of the T is cut away to form a beveled stop-face 109 with which a setting member 111 is adapted to contact by being swung angularly toward it in a manner which will presently be described. Normally the setting member 111 is spaced from the stop-face 109 as shown in Fig. 2. It is not moved into contact with the stop-face, as shown in Fig. 3, until after the T-shaped controller 103 has been set by the movement of the two detectors 81 which engage respectively the thickest and the thinnest locality in the blank 100.

The mounting and setting of this T-shaped controller will now be described. The spindle 105, which supports the controller, is rotatable in a sleeve 113 which is itself rotatable in an upright bearing in the frame 107 of the machine. The sleeve has at its lower end an oblique slot 115 into which extends a pin 117 carried by the spindle 105. Fast to the spindle is a gear 119, and fast to the sleeve is a gear 121. It will be evident from this construction that if the gears 119, 121 are rotated the same distance in the direction indicated by the arrow, the vertical position of the spindle will not change; but if the gear 119 is rotated a greater distance than the gear 121, the spindle will rise and raise the T-shaped controller 103 with it. Slidably mounted in horizontal guideways in the frame of the machine are two racks one of which, 123, engages the gear 119 and the other of which, 125, engages the gear 121, both gears being engaged on the same side so that pulling the racks to the right (as viewed in Fig. 5) will rotate the gears in the direction indicated by the arrow. Integral with the forward end of the rack 123 is a bar 127, and integral with the forward end of the rack 125 is a bar 129, the bars being urged at all times toward each other by a compression spring 131 which is fast at one end to a bracket carried at the rear end of the rack 123 and at the other end to the bar 129 which is integral with the rack 125. Located between the bars are lugs 133 formed on the rear ends

of slides 135. These slides are mounted side by side in a suitable guideway formed in the frame of the machine; and normally, that is when the detectors 81 are in their lowered position, the lugs 133 are held in alignment by engagement of rolls 139 with cam rods 141 under the influence of springs 155. When, however, the detectors 81 are raised into contact with an uneven blank, as shown in Fig. 3, the positions of the lugs 133 depend upon the positions of the detectors. To that end each slide 135 has a recess 137 in which is mounted an idle roll 139, and extending through each recess is the head of a cam rod 141 arranged to slide vertically in suitable bearings in the machine. The lower end of each cam rod is forked to receive a pin 143 carried at the rear end of a lever 145 which is fulcrumed near its middle upon a rod 147. Each lever 145 has at its forward end a fork to receive a pin 149 carried by an arm 151 which is fast to the lower end of stem 87 of one of the yokes 83 in which the detectors 81 are mounted. The forward ends of the slides 135 carry small guide rods 153 which pass through holes in a part of the frame 107 of the machine. Coiled springs 155 encircle the rods and press the rolls 139 of the slides at all times against the inclined faces of the cam rods 141 and thus maintain the racks 123, 125 in the positions shown in Fig. 2 when no blank is present in the machine.

Considering now Fig. 3 in which the right-hand detector 81 is shown in engagement with the thinnest locality of the blank 100 which is engaged by any of the detectors, and the left-hand detector is shown in engagement with the thickest locality, it will be seen that the cam rod 141 which is connected with the right-hand detector 81 has moved downwardly a greater distance than has the cam rod which is connected with the left-hand detector 81. As a result of this, the gear 119 has been rotated a greater distance than the gear 121, the pin 117 has ridden up in the slot 115, and the T-shaped controller 103 has been raised. Thus far only two of the detectors 81 and their associated levers, cam rods and slides have been considered, these two being the ones which engage respectively the thickest and the thinnest locality in a blank. It will now be clear, however, that it is not necessary to consider the other detectors, since the lugs 133 on the other slides would be in contact neither with the bar 127 nor the bar 129 and would therefore have no effect upon the rotation of the gears 119, 121 and consequently no effect upon the height to which the controller 103 was raised. Thus in the case in which one of the detectors engages the thinnest locality and one the thickest locality, the controller 103 will be raised a distance proportionate to the difference in height of these two detectors.

tors, that is a distance proportionate to the thickness-difference of the blank. It should now be clear that in every case the distance through which the controller 103 will be raised will be proportionate to the thickness-difference of the blank which is engaged by the detectors. This is true of the case (to be considered later) of the blank which has no thickness-difference, since in such case the controller 103 will not be raised at all.

After the controller 103 has been raised or set in the manner which has been described, it is locked temporarily in this position by a stepped wedge 157. This wedge 15 (see Figs. 3 and 7) is slidable in a guideway in the frame of the machine and is carried at the upper end of a lever 159 the hub of which is fulcrumed about a rock-shaft 161 and has a tail 163 arranged to be engaged by a cam 165 mounted upon the rotary shaft 67. A spring 167 urges the wedge at all times to move beneath the right-hand end of the head of the T-shaped controller 103, the cam 165 being shaped to hold the wedge away from the controller until the controller has been raised as has been described above. At the proper time the cam 165 permits the wedge to be projected beneath the controller and to be held beneath it while the setting member 111 (Figs. 2 and 3) operates to set the upper blank-engaging member or plate 17 of the splitting mechanism. Specifically the tail 163 of the lever 159 rides off from the raised portion of the cam 165 as soon as a blank is fed to the testing mechanism so that the wedge 157 is free to be moved progressively beneath the controller 103 as the controller rises.

The setting member 111 is formed upon the upper end of a lever 169 the hub of which is fulcrumed upon the rock-shaft 161 and has a tail carrying a roll 171 arranged to run upon a cam 173 which is fast to the shaft 67. A spring 175, acting upon the tail of the lever below the roll 171, urges the setting member at all times toward the oblique stop-face 109 on the controller 103. The cam 173 is so shaped as to hold the setting member 111 away from the stop-face 109 until the controller 103 has been raised into proper position and the wedge 157 has been projected beneath the head of the controller so as to hold it firmly in raised position. The setting member, as has been stated, is formed on the upper end of a lever 169. Also formed upon the upper end of this lever is a yoke 177 (see Fig. 2) the arms of which have slots in their upper ends to receive the trunnions 179 at the opposite ends of a wedge-carrier 181. This wedge carrier has integral with it two arms each of which is formed with two wedges 183, each arm having a flat upper surface which bears against a corresponding surface formed on the under side of a bearing block

185 carried by the frame 107 of the machine. The wedges 183 rest upon rolls 187 which are mounted in ears formed on the upper member 17 of the skiving mechanism. This upper member 17 has fast to or integral with it two uprights 189 which are slotted to receive guides formed on the frame 107 of the machine. A cross-bar 191 connects the tops of the uprights; and springs 193 are provided, as shown, which at all times 75 urge the cross-bar 191 and consequently the member 17 upwardly. Normally, the member 17 is in raised position since the comparatively thin portions of the wedges are in engagement with the rolls 187; but when 80 the setting member 111 is permitted to be moved into contact with the stop-face 109 of the controller 103 by the spring 175, the wedges are pulled forward so as to move the member 17 downwardly and hold it rigidly 85 from upward movement. As has been explained above, the parts are constructed and proportioned so that the member 17 is forced downwardly until the distance from the plane of the cut of the knife to a 90 plane which would pass through the lower elements of the rolls 29 if said rolls were occupying their uppermost positions with the blocks 23 resting firmly against the top walls of the sockets in which they are 95 mounted, is equal to the amount of difference in thickness between the thickest and the thinnest localities of the blank.

The lower blank-engaging member 19 comprises a thick plate having depending 100 from its under side two upright bars one of which is shown at 197, said bars being vertically slidable in guideways formed in the frame of the machine. A cross-bar 199 connects these upright bars; and a socketed 105 cylindrical member 201 is integral with the plate and with the cross-bar 199. Inserted in the socket in this member 201 is a heavy spring 203, and extending into the base of the socket and into contact with the lower 110 end of the spring is a plunger 205 having driven into it a pin 207 which extends through a vertical slot in one wall of the socket, the plunger having a slot in its lower end to receive the outer end of a supporting arm 209 which is fast to a rock-shaft 211. This rock-shaft has fast to its outer end a ratchet 213 having a single tooth which is adapted to be engaged by a spring-pressed 115 pawl 215. In Fig. 2, this pawl is shown as 120 being held out of operative position by a member the operation of which will be described later since it functions only in special cases. The pawl is mounted in a pawl carrier 217 loose on the rock-shaft 211 and pivoted to one end of a link 219, the other end of which is pivoted to an arm 221 the hub of which is fast to a sleeve 223, the sleeve being loosely mounted on a rod 225 and having integral with it an upright arm 125 130

227 to which is pivoted one end of a cam rod 229, the other end of the cam rod carrying rolls 230 and 231 which run on a cam 233 fast to the rotary shaft 67. The cam 5 233 is so shaped that after the blank has been tested, the upper blank-engaging member 17 of the splitting mechanism set and the blank fed part way between the blank-engaging members, the cam rod 229 is 10 pulled to the right, thereby causing the link 219 to move to the right and the pawl 215 to rotate the one-toothed ratchet 213 a short distance in the direction indicated by the arrow. This rocks the shaft 211 and causes 15 the outer end of the arm 209 to rise thereby raising the lower blank-engaging member 19 20 yieldingly through the heavy spring 203, this movement being so timed that the member 19 reaches its uppermost position, which 25 in every case is determined by the thickness of the blank, just before the front end of the blank reaches the knife. The power driven rolls 31 then feed the blank to the knife.

30 In order to hold the lower member 19 with its rolls 31 rigidly from vertical movement during the splitting or evening operation, there are formed on the back sides of each of the upright slides 197 teeth which are engaged at the proper time by locking pawls. In Fig. 8 the teeth formed on the back side of one of the slides 197, together with the pawls which co-operate with those teeth, are shown, it being understood that similar teeth 35 are formed on the back side of the other slide 197 with which similar pawls co-operate. Inasmuch as these two locking mechanisms are, or may be, duplicates of each other, only one has been shown. Referring 40 now to the details of construction of the locking mechanism shown in Fig. 8, formed on the back side of the arm 197 are a series of downwardly pointing teeth 235 and a series of upwardly pointing teeth 236. Adapted 45 to co-operate with the downwardly pointing teeth 235 are a plurality of pawls 239, three being shown, each having upwardly pointing teeth; and adapted to co-operate with the upwardly pointing teeth 50 236 are three pawls 238 having downwardly pointing teeth. By providing three pawls in each case the rows of teeth of which are out of alignment with one another, a finer locking adjustment can be secured with 55 teeth of a given size than would be practicable were there but two pawls in all, one for the teeth 235 and one for the teeth 236. The pawls of both sets are slotted horizontally to receive a pin 241 which is rigidly 60 mounted in the pawl carrier 243 and serves as an abutment for springs 244 one for each pawl. The pawl carrier 243 has depending from each end an integral arm, one of which is shown at 245, the hubs of which are loose 65 on the rod 225.

Pivoted to an arm 227 and extending through a hole in an ear on the arm 245 is a pin 247. A coiled spring 249 encircles the pin between the arm 227 and the ear on the arm 245, a thumb-nut 251 being threaded 70 on the end of the pin. The purpose of the thumb-nut is to adjust the pawl carrier 243 into the desired position. As has been explained above, the arm 227 is pulled to the right to cause the lower blank-engaging 75 member 19 to be raised. When this occurs, the pawl carrier 243 is pushed yieldingly to the right to bring the teeth of its pawls into co-operation with the teeth 235, 236 formed on the slides 197, the pawl carrier 80 being held in this position during the skinning operation and released at the end of that operation by the action of the cam 233 on the roll 230.

The parts of the locking mechanism which has just been described, as well as those of the mechanism for raising the lower blank-engaging member 19 and for permitting it to fall are so constructed and arranged that they operate as follows. When the rod 229 85 is pulled to the right thereby swinging the arms 227 and 221 to the right, the pawls 238, 239 are not at first engaged with the teeth 235, 236. The first part of this rocking movement of the arm acts through the 90 rod 219 and pawl 215 to turn the shaft 211 in a clockwise direction thereby causing the arm 209 to raise the plunger 205 and thereby the heavy spring 203 and the lower blank-engaging member 19 until the blank 95 is pressed firmly up against the upper blank-engaging member and the spring 203 somewhat compressed. Up to this point, the locking pawls 238, 239 have not engaged the teeth 236, 235. However, as the arm 209 100 continues its upward swinging movement and compresses the spring 203 a little more, the pawl carrying arm 227 is swung far enough to cause the locking pawl to engage 105 their respective teeth on the slide 197 and thereby lock the lower blank-engaging member from movement either up or down. The cam 233 is shaped to hold the locking pawls 237, 238 in engagement with the teeth 236, 235 during the splitting or evening of the 110 blank and then to move the rod 229 to the left. The first part of this movement releases the pawls and relieves the compression of the heavy spring 203, and the latter part of this movement permits the lower 115 blank-engaging member to fall into lowered position ready to receive the next blank. By manipulating the thumb nut 251, the locking and unlocking action of the pawls 237, 238 may be properly timed.

120 Thus far it has been assumed that the blanks which pass through the machine are all uneven, that is that each blank is not of uniform thickness throughout. In practice, however, many of the blanks are of uniform 125

or substantially uniform thickness throughout; and it is desirable that no stock should be removed from such blanks. Accordingly provision is made whereby, when a blank 5 of uniform thickness is encountered, the lower member 19 of the skiving mechanism is not raised at all, so that the blank is fed freely over it and beneath the knife without being skived. This result is accomplished 10 by holding the pawl 215 out of operative position, as shown in Fig. 2, so that it cannot engage the one-tooth ratchet 213, and the supporting arm 209 will not be raised. To this end (see Fig. 2) a shield 15 253 slotted to receive the end of the rock-shaft 211 is carried at one end of a link 255 the other end of which is pivoted to the lower end of an arm 257 the upper end of which is fast to the rock-shaft 161 so 20 that, when the rock-shaft is rocked in the direction indicated by the arrow, the shield 253 occupies the position shown and holds the pawl 215 in inoperative position. The rocking of the shaft in this manner is governed 25 by a finger 259 which is carried by a block 261 adjustably held by a screw bolt 263 at the slotted upper end of a lever 265 the hub of which is pinned to the rock-shaft 161 and has a tail adapted to co-operate 30 with a cam 267 fast to the rotary shaft 67. A spring 269 acts at all times to pull the upper part of the lever 265 toward the front of the machine and thereby to move the finger 259 toward or over the controller 103 according to the position of the controller. 35

The operation of the mechanism which has just been described is as follows. With the parts of the machine in the positions shown in Fig. 2 in which no blank is being tested or operated upon, the finger 259 extends 40 over the controller 103 and the shield 253 holds the pawl 215 in inoperative position. During the time that the feed slide 13 is advancing a blank to the testing mechanism, the cam 267 operates upon the tail of the lever 265 and rocks the lever, and with it the rock-shaft 161, in a direction to move the finger 259 toward the rear of the machine until it no longer extends over the controller 103; and the same rocking of the 45 shaft 161 moves the shield 253 toward the front of the machine and thereby disengages the pawl and permits it to move into operative position. The cam 267 is shaped to hold the finger and shield in these positions during the testing of the blank and the effect of the testing upon the controller 103. If the blank is not of uniform thickness throughout, that is if it has a thickness-difference, the controller 103 will be raised 50 into the path of the finger 259 so that, when presently the cam 267 has rotated far enough to permit the tail of the lever 265 to fall and the spring 269 is free, so far as the cam 55 is concerned, to pull the lever back into the

position shown in Fig. 2, the end of the finger 259 will encounter one face of the T-shaped controller 103, as shown in Fig. 3. This will arrest the rotation of the rock-shaft 161 before the shield 253 has been moved far enough to raise the pawl 215 to inoperative position. Consequently, if the blank which is being tested has a thickness-difference, the finger 259 and its associated pawl-throw-out mechanism will not affect 75 the operation of the skiving mechanism, and the blank will be skived, as has been described so as to produce a finished article of the maximum uniform thickness possible.

On the other hand, if the blank which is being tested is of uniform thickness—in which case it is desirable not to skive it at all—the controller 103 will not be raised at all since the gears 119, 121, whose differential rotation causes the raising of the controller, will both be rotated equally in the same direction. When, therefore, the cam 267 reaches the proper position, the spring 269 will be permitted to pull the lever 265 toward the front of the machine so as to 80 rock the shaft 161 far enough to push the shield 253 beneath the pawl 215 and hold it in inoperative position. With the pawl thus held, the movement of the link 219 toward the rear of the machine will not rock the 85 shaft 211 and consequently the lower member 19 of the skiving mechanism will not be raised at all. The blank will thus be delivered upon the power driven rolls 31 and fed under the knife without being skived. 90

In order to promote clearness of explanation the operation of the pawl-controlling mechanism, including the finger 259 has just been described in connection with a blank which is of uniform thickness throughout. 105 Of course few blanks are of absolutely uniform thickness, but it is desirable to treat as of uniform thickness blanks whose thickness-difference is small. For example, a heel-lift blank the thickness-difference of 110 which is only one iron (1/48 of an inch) would in many factories be suitable for use without being skived to an absolutely uniform thickness. It is therefore desirable that the machine be capable of being set so 115 that blanks having either a certain amount of thickness-difference or an amount greater than that certain amount will be skived, but that blanks which have thickness-differences less than the certain amount will not be 120 skived. This is the reason that the finger 259 is adjustably mounted on the lever 265. Assuming that with the finger in the adjusted position shown all blanks having any thickness-difference at all will be skived 125 while all blanks of uniform thickness will not be skived, it is only necessary to adjust the finger slightly higher to cause all blanks having a thickness-difference less than a certain amount to pass through the machine 130

without being operated upon by the skiving mechanism. It is thus possible to prevent the skiving of all blanks which, for example, have a thickness-difference of one iron or less by adjusting the block 261 which carries the finger 259; and to facilitate such adjustment the block has upon it a scale which may represent irons and half-irons, and the lever has a mark to co-operate with the scale.

Referring now more particularly to Fig. 1, with occasional reference to Fig. 1, the manner in which the rolls 31 of the lower blank-engaging member 19 are driven will be described. Mounted loosely on the shaft 67 is an arm 279 having pivoted to its upper end one end of a gear-carrying link 281, the other end of the link being pivoted on the shaft of the first roll 31, there being five of these rolls. The link carries two gears 283, 285, the gear 283 meshing with the driven gear 69, and the gear 285 meshing on one side with the gear 283 and on the other with a gear 287 which is fast to one end of the shaft of the first roll 31. Referring now entirely to Fig. 6, the first roll 31 has keyed on its left-hand end a gear 289 which meshes with an idle gear 291 loose on the shaft of the second roll. On the left-hand end of the third roll is keyed a gear 293 which meshes with an idle gear 295 loose on the shaft of the fourth roll, the latter gear meshing with a gear 297 keyed to the shaft of the fifth roll. With the construction thus far described, the first, third and fifth rolls will be driven all in the same direction. In order to drive the second and fourth rolls in the same direction, the shaft of the third roll has fast to its right-hand end an internal gear 299 with which mesh gears 301, 303 fast respectively to the right-hand ends of the shafts of the second and fourth rolls. With this construction the rolls 31 are all driven at the same speed in the same direction, and the mesh of the various gears is not disturbed by the vertical movement of the member 19.

The operations of the various mechanisms which make up the machine have been described above one by one. The general operation of the machine will now be described briefly, first with reference to a blank which is not of uniform thickness throughout and second with reference to a blank which is of uniform thickness throughout since the description will thus be much simplified. It should be understood, however, as has been explained above, that a more accurate division of the blanks into classes would place in one class the blanks which have thickness-differences great enough to cause them to be operated upon and in another class those which do not, since whether or not a blank which has a thickness-difference will be operated upon depends upon the height at

which the finger 259 is set, and this may be set to any predetermined standard.

Assuming that the lowermost blank in the magazine is uneven in thickness, the general operation of the machine is as follows. The blank is fed into position beneath the plate 15 and above the detecting rolls 81 and permitted to remain stationary during the testing operation. During this feeding of the blank, or at least before the detecting rolls have moved upwardly, the cam 267 has moved into position to withdraw the finger 259 from above the controller 103. While the blank remains stationary beneath the plate 15, the detecting rolls 81 are forced up against the under side of the blank, the two rolls 81 which engage respectively the thickest and the thinnest localities standing then respectively at levels lower and higher than any of the others. These two rolls by their positions and the resulting positions of their associated levers 145, cam rods 141 and slides 135 pull the racks 123 and 125 different distances toward the front of the machine, the levers, cam rods, etc., associated with the other three detecting rolls 81 being without effect. Pulling the racks 123, 125 different distances produces differential rotation of the gears 119, 121, and through the pin and slot connection 117, 115 raises the T-shaped controller 103 a distance proportional to the difference in extent of the rotation of the gears 119, 121. Meanwhile the wedge 157 has been released by the cam 165 and is now forced beneath the right-hand end of the head of the controller 103 so as to hold it in raised position. The cam 267 now releases the lever 265 on which the finger 259 is mounted, but the finger and lever are prevented from moving a distance effective to bring the shield 253 into operation by reason of the end of the finger coming into contact with the controller as shown in Figs. 3 and 5. The cam 173 now releases the lever 169 which permits the face of the setting member 111 to move toward the front of the machine until it is stopped by contact with the stop-face 109 of the controller 103. This movement of the setting member pulls the wedges 183 toward the front of the machine and lowers the upper blank-engaging member 17 into proper position. The blank is fed forward until its leading edge is close to the knife, whereupon the cam 233, through the links 229, 219 and pawl 215 rocks the shaft 211. The first part of this rocking movement raises the lower blank-engaging member 19 to press the blank against the upper blank-engaging member 17; and the last part of this movement causes the pawls 238, 239 to lock the lower blank-engaging member rigidly from vertical movement. The power-driven rolls 31 which are then in engagement with the under side of the blank feed it to the knife

which skives it to a uniform thickness. In the further rotation of the shaft 67 the various parts are brought back to the positions shown in Fig. 2 ready to start another 5 cycle.

Assuming now that the next blank which is fed is even in thickness, that is of a uniform thickness throughout, the detecting rolls 81, when brought up against its under 10 side, will all stand at the same level. Consequently the gears 119, 121 of the controlling mechanism will both be rotated through the same distance and the controller 103 will not be raised. Therefore when, presently, 15 the cam 267 releases the lever 265, the finger 259 will not contact with the head of the controller but will permit the lever to be rocked, and with it the rock-shaft 161, until the shield 253 raises the pawl 215 into 20 operative position and holds it there. The blank is now fed forward as before until its leading edge is close to the knife; but, owing to the fact that the pawl 215 is being held inoperative, the lower blank-engaging member 25 is not raised by the operation of the cam 233, and consequently the blank is fed beneath the knife without being skived.

Although the invention has been set forth as embodied in a particular machine, it 30 should be understood that the invention is not limited in the scope of its application to the particular machine which has been shown and described. The method of testing blanks for variation in a selected characteristic and of first testing them and then operating with respect to this characteristic forms the subject-matter of United States Letters Patent No. 1,448,045, granted March 13, 1923, on an application filed in 35 my name; and a machine for testing the blanks for variation and then grading them in accordance with the variation forms the subject-matter of United States Letters Patent No. 1,442,233, granted Aug. 16, 1922, on 40 an application filed in my name.

Having thus described my invention, what I claim as new and desire to secure by Letters Patent of the United States is:

1. A machine of the class described, having in combination, means for determining the amount of variation of an article with respect to a selected characteristic, and means controlled by the variation-determining means for changing that characteristic. 50

2. A machine of the class described, having in combination, means for determining the amount of variation of an article with respect to a selected characteristic, and means controlled by the variation-determining means for rendering it uniform in that characteristic. 55

3. A machine of the class described, having in combination, means for determining the amount of variation of an article with respect to a selected characteristic, and 60

means controlled by the variation-determining means for removing stock from the article to render it uniform in that characteristic.

4. A machine of the class described, having in combination, a plurality of devices for detecting a selected characteristic of an article at spaced localities, and means responsive to the difference in the amount of the findings of the detecting devices for 70 changing that characteristic.

5. A machine of the class described, having in combination, a plurality of devices for detecting a selected characteristic of an article at spaced localities, and means responsive to the difference in the amount of the findings of the detecting devices for 80 rendering it uniform in that characteristic.

6. A machine of the class described, having in combination, a plurality of devices 85 for detecting a selected characteristic of an article at spaced localities, and means responsive to the difference in the amount of the findings of the detecting devices for removing stock from the article to render it 90 uniform in that characteristic.

7. A machine of the class described, having in combination, means for determining the amount of difference in thickness between a plurality of localities of a blank, 95 and means controlled by the amount of difference as found by the determining means for skiving the blank to a uniform thickness.

8. A machine of the class described, having in combination, mechanism for determining the amount of difference in thickness between a plurality of localities of a blank, skiving mechanism, and connections 100 between the determining mechanism and the skiving mechanism for setting the skiving mechanism in accordance with the amount 105 of the thickness-difference.

9. A machine of the class described, having in combination, a plurality of detectors 110 adapted to engage a blank, means for causing the detectors to be pressed against the blank, and means for reducing the thickness of the blank in accordance with the amount of difference between the findings 115 of the detectors.

10. A machine of the class described, having in combination, a plurality of detectors adapted to engage a blank, means for causing the detectors to be pressed against the blank, and means for skiving the blank in 120 accordance with the amount of difference between the findings of the detectors.

11. A machine of the class described, having in combination, a number of detectors 125 greater than two adapted to engage a blank at spaced localities to determine a characteristic of the blank at those localities, and means for skiving the blank in accordance with the amount of difference between the 130

maximum and minimum findings of the detectors constructed and arranged to be unaffected by the intermediate findings.

12. A machine of the class described, having in combination, mechanism for testing a blank to determine the amount of variation in a selected characteristic of the blank, mechanism for changing the selected characteristic, a controller the position of which governs the extent of the change produced, and means operated by the testing mechanism for adjusting the controller in accordance with the amount of variation found by the determining means.

13. A machine of the class described, having in combination, a support against which a blank may be pressed, a plurality of individually movable yielding detectors, a carrier in which the detectors are mounted, means for moving the carrier toward the support to cause the detectors to press against the blank and thereby determine the difference between the maximum and minimum thickness of the blank at the localities engaged, a controller, means including a plurality of levers, one for each detector, for adjusting the controller in accordance with the amount of the difference, skiving mechanism including a cutter and two blank-engaging members, and means for adjusting one of the members in accordance with the adjusted position of the controller.

14. A machine of the class described, having in combination, a cutter and two members for advancing a blank to the cutter, said members being located one on one side of the plane of the cut and one on the other, means arranged to permit adjustment first of one member and then of the other toward the plane of the cut, and means for holding both members rigidly from movement away from said plane during the cutting operation, the finally adjusted positions of the members determining the thickness to which the blank will be split.

15. A machine of the class described, having in combination, a cutter and two members for advancing a blank to the cutter, yielding pressers carried by one of the members, means arranged to permit adjustment first of one member and then of the other toward the plane of the cut, and means for holding both members rigidly from movement away from said plane during the cutting operation.

16. A machine of the class described, having in combination, a cutter, blank-engaging members for engaging a blank during the cutting operation and advancing it to the cutter, means for adjusting one of said members into the desired relation with respect to the cutter, the members being at this time spaced apart a distance greater than the thickness of the blank to be operated upon so that the blank may be placed

between them, and means for moving the other member toward the adjusted member until the blank is firmly engaged by both members, the finally adjusted positions of the members determining the thickness to which the blank will be split.

17. A machine of the class described, having in combination, a cutter, blank-engaging members for advancing a blank to the cutter, means for adjusting one of said members into the desired relation with respect to the cutter, the members being at this time spaced apart a distance greater than the thickness of the blank to be operated upon so that the blank may be placed between them, means for yieldingly moving the other member toward the adjusted member until the blank is firmly engaged by both members, and means for locking the yieldingly moved member from movement away from the blank during the cutting operation.

18. A machine of the class described, having in combination, a cutter, and a pair of blank-engaging members for advancing a blank to the cutter, one of said members comprising individually yielding pressers spaced widthwise and lengthwise of the blank and the other comprising spaced feed rolls, the blank-engaging elements of which are located in a common plane.

19. A machine of the class described, having in combination, a cutter, a pair of blank-engaging members for advancing a blank to the cutter, one of said members comprising individually yielding pressers spaced widthwise and lengthwise of the blank and the other comprising spaced feed rolls, the blank-engaging elements of which are located in a common plane, and means for adjusting the members in succession.

20. A machine of the class described, having in combination, a cutter, blank-engaging members for advancing the blank to the cutter, the finally adjusted positions of said members determining the thickness to which the blank will be split, means for adjusting one of the members into the desired position with respect to the edge of the cutter and for holding it rigidly from movement away from the cutter, and means capable of being operated thereafter for moving the other member toward the first named member and for holding it also rigidly from movement away from the cutter.

21. A machine for skiving a blank of uneven thickness to an even thickness, having in combination, a knife, a gage member the blank-engaging face of which is normally spaced from the plane of the cut of the knife a distance greater than the amount of the difference in thickness between the thickest and the thinnest localities of the blank, a feed member adapted to co-operate with the gage member in advancing the blank to the knife, means for adjusting the

gage member toward the plane of the cut of the knife, and means for thereafter moving the feed member toward the gage member to cause the two members to grip and feed the blank.

22. A machine for operating upon a blank of uneven thickness, having in combination, a cutter, and members located in front of the cutter for engaging the blank on both sides, means for adjusting one of the members into a position in which its blank-engaging face is spaced from the plane of the cut of the cutter a distance substantially equal to the amount of difference in thickness between two localities of the blank, and means for causing the blank to be gripped between the members and advanced by them to the cutter.

23. A machine for operating upon a blank of uneven thickness, having in combination, a cutter, a gaging member located in front of the cutter and having its face spaced from the plane of the cut a distance substantially equal to the amount of difference in thickness between two localities of the blank, and means for pressing the blank against the gaging member and feeding the blank while so pressed to the cutter.

24. A machine for operating upon a blank of uneven thickness, having in combination, a cutter, a gaging member located in front of the cutter and having its face spaced from the plane of the cut a distance substantially equal to the amount of difference in thickness between the thickest and thinnest localities of the blank, and means for pressing the blank against the gaging member and feeding the blank while so pressed to the cutter.

25. A machine for operating upon a blank of uneven thickness, having in combination, a cutter, a gaging member and a feed member for presenting the blank to the cutter, the gaging member comprising a plurality of rigidly mounted pressers the blank-engaging elements of which lie in a common plane when the pressers are fully retracted, and the feed member comprising a plurality of rigidly mounted pressers, the members being adjusted into such position that the distance between a plane passed through the blank-engaging elements of the rigidly mounted pressers and a plane passed through the blank-engaging elements of the yieldingly mounted pressers when in their retracted positions is substantially equal to the thickness of the thickest locality of the blank, and means for maintaining the members in such relative positions during the cutting operation.

26. A machine for skiving an uneven blank, having in combination, a skiving knife, two opposed blank-engaging members for advancing the blank to the knife, yielding pressers mounted in one member in such

manner that in their fully retracted positions they present a rigid blank-engaging surface, means for adjusting the member having the pressers into a position relative to the knife such that the blank-engaging surface formed by the pressers when fully retracted is spaced from the plane of the cut of the knife a given distance, and means for moving the other member toward the member in which the pressers are mounted.

27. A machine for skiving an uneven blank, having in combination, a skiving knife, two opposed blank-engaging members for advancing the blank to the knife, yielding pressers mounted in one member in such manner that in their fully retracted positions they present a rigid, blank-engaging surface, means for adjusting the member having the pressers into a position relative to the knife such that the blank-engaging surface formed by the pressers when fully retracted is spaced from the plane of the cut of the knife a distance proportional to the difference in thickness between two localities of the blank, and means for moving the other member toward the member in which the pressers are mounted.

28. A machine for skiving a blank of non-uniform thickness, having in combination, a skiving knife, means for forcing the blank against the edge of the knife, said means consisting of a member arranged to engage that side of the blank from which the skiving is to be removed and a member for engaging that side of the blank which is to be part of the finished article, and means for adjusting the first-named member into a position in which its blank-engaging face is spaced from the plane of the cut of the knife a distance substantially equal to the difference in thickness between two localities of the blank.

29. A machine for skiving a blank of non-uniform thickness, having in combination, a skiving knife, means for presenting the blank to the knife, said means comprising a member arranged to engage that side of the blank from which the skiving is to be removed and a member for engaging that side of the blank which is to be part of the finished article, means for adjusting the first-named member into a position in which its blank-engaging face is spaced from the plane of the cut of the knife a distance substantially equal to the difference in thickness between two localities of the blank, and means for thereafter moving the other member toward the first-named member.

30. A machine for removing a skiving from a blank of sheet material to reduce the blank to a uniform thickness throughout, having, in combination, a skiving knife, a pair of members for presenting an edge of the blank to the knife and for feeding the blank in a path parallel to the plane of the

- cut of the knife during the skiving operation, each member being provided with means for engaging the blank during the cutting operation throughout an area sufficient to maintain the uncut portion of the blank substantially flat, and means for rigidly supporting the members from movement away from the knife during the skiving operation.
31. A machine for operating upon a blank of uneven thickness, having in combination, testing mechanism for determining the thickness-difference of the blank, skiving mechanism including a cutter and two blank-engaging members for advancing the blank to the cutter, and means including the testing mechanism for moving first one member and then the other into proper position with respect to the cutter.
32. A machine for operating upon a blank of uneven thickness, having in combination, testing mechanism for determining the thickness-difference of the blank, skiving mechanism including a cutter and two blank-engaging members for advancing the blank to the cutter, means including the testing mechanism for moving first one member and then the other into proper position with respect to the cutter, and means for holding both members from movement away from the blank during the cutting operation.
33. A machine for operating upon a blank of uneven thickness, having in combination, testing mechanism for determining the thickness-difference of the blank, skiving mechanism including a cutter, a blank-engaging member comprising a plurality of yielding pressers and a blank-engaging member having a rigid blank-engaging face, and means for adjusting the first-named member in accordance with the determination of the testing mechanism.
34. A machine for operating upon a blank of uneven thickness, having in combination, testing mechanism for determining the thickness-difference of the blank, skiving mechanism including a cutter, a blank-engaging member comprising a plurality of yielding pressers and a blank-engaging member having a rigid blank-engaging face, means for adjusting the first-named member in accordance with the determination of the testing mechanism, and means for thereafter moving the other member toward the adjusted member.
35. A machine for operating upon a blank of uneven thickness, having in combination, testing mechanism for determining the thickness-difference of the blank, skiving mechanism, means for adjusting the skiving mechanism in accordance with the determination of the testing mechanism, and means for feeding the blank first to the testing mechanism and then to the skiving mechanism.
36. A machine for operating upon a blank of uneven thickness, having in combination, testing mechanism for determining the thickness-difference of the blank, skiving mechanism, means for adjusting the skiving mechanism in accordance with the determination of the testing mechanism, a magazine for holding a stack of blanks, and means for feeding the blanks one by one first to the testing mechanism and then to the skiving mechanism.
37. A machine for operating upon a series of blanks, having in combination, means for testing each blank to determine whether it is uniform or non-uniform in a selected characteristic, mechanism capable of changing the characteristic, means for causing the mechanism to operate upon the blanks which are non-uniform and other means for preventing the mechanism from operating upon the blanks which are uniform.
38. A machine for operating upon a series of blanks, having in combination, means for testing each blank to determine whether it is uniform or non-uniform in thickness, mechanism capable of changing the characteristic, means for causing the mechanism to operate upon the blanks which are non-uniform and other means for preventing the mechanism from operating upon the blanks which are uniform.
39. A machine for operating upon a series of blanks having, in combination, means for testing each blank to determine whether it is uniform or non-uniform in thickness, a skiving knife, a gage member located above the plane of the knife, a co-operating feed member located below the plane of the knife and normally spaced below the gage member a distance sufficient to permit a blank to pass freely beneath the knife, and means responsive to the operation of the testing mechanism upon a blank of non-uniform thickness for raising the feed member and responsive to the operation of the testing mechanism upon a blank of uniform thickness for preventing the feed member from being raised.
40. A machine of the class described having, in combination, detecting mechanism, skiving mechanism, said skiving mechanism including a gage member which is set in accordance with the determinations of the detecting mechanism and a co-operating feed member which may thereafter be raised to press the blank against the gage member, and means responsive to non-uniformity in thickness of a blank for raising said feed member and responsive to uniformity in thickness of a blank for preventing the feed member from being raised.
41. A machine for operating upon a series of blanks, having in combination, means including a plurality of independently moveable feelers for testing each blank to determine whether it is uniform or non-uniform

- in thickness, skiving mechanism, means for advancing each blank from the testing mechanism to the skiving mechanism, and connections between the two mechanisms responsive to the positions of the feelers constructed and arranged to cause the skiving mechanism to operate upon the non-uniform blanks and to prevent it from operating upon the uniform blanks.
- 5 42. A machine for operating upon a series of blanks, having in combination, means for testing each blank to determine whether it is uniform or non-uniform in a selected characteristic within a predetermined standard, mechanism capable of changing the characteristic and governing means for causing the mechanism to operate upon the blanks which are non-uniform and for preventing the mechanism from operating upon 15 the blanks which are uniform, said governing means including a member adjustable to vary the limit of the standard.
- 20 43. A machine for operating upon a series
- of blanks, having in combination, testing mechanism for determining the thickness-difference of each blank, skiving mechanism, means for setting the skiving mechanism in accordance with this difference, and mechanism for rendering the skiving mechanism inoperative when no thickness-difference is present, said last-named mechanism including a member capable of adjustment to render the skiving mechanism inoperative when a thickness-difference is present in a blank but is less than a predetermined amount.
- 25 44. A machine of the class described, having in combination, means for determining the amount of variation of an article with respect to a dimension thereof, and means 30 controlled by the variation-determining means for effecting a change in the article with respect to that dimension.

In testimony whereof I have signed my name to this specification.

JAMES G. NORTON.
